FORGING MACHINE

William W. Criley, Cleveland, Ohio

Application February 6, 1936, Serial No. 62,641

3 Claims. (Cl. 78—13)

This invention relates to an improvement in forging machines, and more specifically is directed to a device for maintaining rigidity of the blank gripper die carrying parts of the frame of such machines, and designed to facilitate the removal of large forgings, and further to permit access to the dies and blank gripping members.

One object of the present invention is the provision of a transverse tie clamp of special design for forging machines or the like which shall not only effectively prevent springing of the frame and consequent spreading of the blank gripping members when the machine is in operation, but contributes to an improved design of the body of the machine.

Another object of the invention is to provide a transverse tie clamp for forging machines which is especially designed to permit access to the dies and blank gripping members and also to facilitate the removal of bulky forgings from the machine.

In large forging machines of the type disclosed, it is essential to provide a machine having die carrying frame jaws which will not spread or distort under the great forces set up while the machine is in operation.

Applicant is aware that previous attempts have been made in the design of forging machines to make the dies and other parts thereof more accessible than machines heretofore constructed.

Machines have been built without the usual transverse tie members across the side portions of the frame. Such machines, however, are more expensive to manufacture because of the large amount of material necessary. There are inherent difficulties in machining and handling the castings. Moreover, a machine of the above construction must necessarily be so much greater in width than applicant's machine, of a size designed to handle the same work, that the frame must be made in two sections in order to comply with the present railroad shipping clearance requirements. These two sections must be tied together on assembly by several large longitudinal tie members, which is an expensive and unsatisfactory method of connection.

Another object of the invention is to provide a forging machine with a transverse tie clamp which is located as near as possible to the center of transverse pressure and still not interfere with the removal of forgings or the accessibility of dies or the blank gripping members.

Heretofore, the transverse tie members have either passed beneath or above the usual longitudinal tie bar. Those familiar with the art of forging machine construction realize that a defi-

nite clearance must be maintained between the lower edge of the transverse member and the blank gripping die elements of a machine in order to provide accessibility of these elements and also to facilitate removal of the forgings.

A still further object of the invention is to provide a transverse tie clamp which, compared to others, is inexpensive to manufacture and easily applied.

Other objects may be apparent from the following specification, which refers to the accompanying drawings.

In the drawings:—

Fig. 1 is a plan view of a forging machine showing the present invention applied thereto.

Fig. 2 is a front elevation of the machine shown in Fig. 1.

Fig. 3 is a perspective view of the transverse tie clamp.

Fig. 4 is a fragmentary front elevation of a forging machine showing one modification of the tie clamp construction applied thereto.

Fig. 5 is a fragmentary plan view of the device shown in Fig. 4.

Referring to the drawings, a forging with a box-like frame 1 is shown having side portions 2 and 3 extending longitudinally and being spaced to form a work receiving opening indicated at 4 at the front of the machine.

The machine is provided with a pair of blank gripping die members as at 5 and 6, carried in the frame near the front end, one of which may be stationary and the other capable of constrained movement transversely of the machine in a guide-way as at 7.

Each of the blank gripping members 5 and 6 may have one or more horizontal grooves shown at 8 and 11, respectively, formed in the engaging surfaces thereof, which are adapted to register with each other and to produce openings as at 12 for encircling and tightly gripping a portion of blank stock prior to and during the forging operation. The inner end of the openings 12 may terminate in cavities as at 13 into which the portion of the stock is forced to flow under the pressure exerted by the forming die.

Each blank must be firmly held against subsequent movement during the forging operation, in frictional engagement between the blank gripping members by an extremely heavy transverse force applied to the movable member 6. Frequently the magnitude of this force reaches several hundred tons which is sufficient to spring or distort an open type frame so as to cause the gripping members to loosen their hold on the

blank and allow it to slip when the force of the forging die is applied thereto.

Since much of the success of such a forging machine relies on its ability to positively hold these blanks in a definite position, it follows that a large amount of this responsibility depends upon the proper design and construction of a transverse frame reinforcing member or tie clamp, which will hereinafter be described in detail.

A die member as at 14 having a die formation 15 may be removably secured to a cross head 16 and is adapted to register with a cavity as at 13 in the ends of the blank gripping members 5 and 6.

The cross head 16 is constrained to move longitudinally of the machine in a suitable recess 17 which is defined by guides 18 and 21. The cross head is caused to reciprocate between the guides by a connecting rod 22 and a crank shaft 23 which may be driven by a motor and belt, not shown, a pulley 21, shaft 28, pinion 31, and gear 32.

Each of the side portions 2 and 3 may be provided with heavy lugs as at 35 and 36, respectively, which are located forwardly or to the rear of the blank gripping members 5 and 6 as indicated in Fig. 1. The upper faces of the lugs 35 and 36 have formed thereon suitable vertical parallel shoulders as at 37 and 38, respectively.

In Fig. 3 a transverse tie clamp 41 is shown having the lower surfaces adjacent the ends provided with complementary shoulders 42 and 43 which are suitably spaced and adapted to snugly engage the shoulders 37 and 38, respectively.

The end portions of the tie clamp including the shoulders 42 and 43 may be somewhat wider than the intermediate portion 44 in order to provide as large a bearing surface on these shoulders to sustain the great pressure developed without peening down and also to assure transverse alignment thereof with respect to the frame.

The usual transverse tie bars are heavy cylindrical members threaded on both ends and provided with large nuts. These bars project through suitable openings in lugs located adjacent the sides of the frame. The transverse load is carried entirely by the threads on the bars.

In applicant's tie clamp, however, it will be seen that a much less expensive construction is employed and a far greater efficiency obtained in regard to strength and maintenance. The transverse load is carried entirely by the registering shoulders on the lugs and the tie clamp which is held in place on the lugs by cap screws 51 which may be easily and quickly removed and replaced by the use of a wrench of a size not difficult to handle.

The tie clamp 41 is shown somewhat enlarged near the center in the form of a hub as at 45 to provide an opening 46 for embracing a longitudinal tie bar 47 which acts to reinforce the frame across the guideway 7 and the opening 4.

From an examination of Fig. 2, it will also be seen that through the use of the clamp 41 which embraces the member 47, the frame height may be considerably less than that of a machine employing the usual heavy cylindrical transverse member which lies entirely above the longitudinal member 47, and also the frame strength is greatly improved. Furthermore, it is possible to materially reduce the total weight and cost of a machine by the use of such a clamp.

Figs. 4 and 5 illustrate a modification of the

tie clamp shown in Figs. 1, 2, and 3, in which the end is pivoted by a hinge pin 55 projecting through a pair of spaced lugs 56 on one side of the machine frame, and also through a suitable opening provided in one end of the clamp 57 which lies in the space between lugs 56. Inwardly tapering shoulders 58 formed on lugs 61 are adapted to register or abut with corresponding shoulders 62 located adjacent either end of the clamp 57.

The tapering shoulders 58 and 62 facilitate swinging the clamp member 57 open and closed with respect to the frame, and also assure a tight-fitting metallic contact between the abutting surfaces.

The end of the tie clamp opposite the hinge may be secured to the lug 61 or the machine frame as by screws 63. It will be noted that in this modification also the shoulders 58 and 62 carry the entire transverse tie clamp load in the same manner as those in the heretofore described form.

The transverse tie clamp 57 must necessarily lie above the longitudinal tie bar 47 to allow the transverse clamp to be swung open as shown by dotted lines in Fig. 4, and to permit further accessibility to the working parts of the machine. The size and weight of the clamp on a machine of the present type are such as to require the assistance of a crane or other hoisting device to remove and replace them.

In this modification also the head room of the frame is less and the strength greater than a machine having the usual type and size of transverse bar lying above the longitudinal bar because the member 57 is slightly arched, as shown in Fig. 4, to clear the member 47 and to bring the abutting shoulders nearer the center of transverse pressure.

It will also be seen that applicant's clamp does not hinder the removal of large forgings from the machine, which is an awkward and time-consuming operation in machines where the transverse rod lies beneath the longitudinal member and thus only a short distance above the work receiving opening.

From the foregoing description, it will be seen that the location of applicant's transverse tie clamps permits adjustment and replacement of the blank gripping members to be made more quickly and conveniently than such changes on a machine employing the usual type of transverse clamp. Furthermore, the present tie clamp is more effective in maintaining rigidity of the frame than is a conventional reinforcing member because of the relatively close proximity of applicant's device to the center of transverse pressure.

In a machine employing the usual transverse tie bar which is located above the longitudinal bar, the forces may be sufficient to cause the frame to spring due to the inherently great distance of such a bar from the center of pressure in the machine frame.

It will also be seen that applicant's tie clamp does not hinder the removal of large forgings from the machine, as would be the case should the transverse tie rod be placed beneath the longitudinal tie rod.

The present showings are not intended to specifically limit the construction thereto, since other forms may occur to those skilled in the art without departing from the scope of the invention as defined in the annexed claims.

Having thus described my invention, what I claim is:

1. In a horizontal forging machine having a horizontal frame, one portion thereof being substantially U-shaped in upright cross section, transversely spaced lugs at the free ends of the U-shaped portion respectively and extending upwardly of the frame and terminating longitudinally of the frame short of the ends of the frame, clamping dies relatively movable laterally of the frame within the U-shaped portion and buttressed laterally thereby, a ram and cooperating die relatively movable longitudinally of the frame, whereby said U-shaped portion is stressed during operation of the ram and dies and tends to spread transversely of the frame, a longitudinal tie bar reinforcing the frame longitudinally, a transverse tie member having inwardly facing shoulders near the ends thereof, said lugs having outwardly facing shoulders in abutting relation to the inwardly facing shoulders, said transverse tie member having a hole extending longitudinally of the frame for accommodating the longitudinal tie bar, said longitudinal tie bar being offset laterally of the frame from the work engaging plane of the gripping dies, said transverse tie member being movable along the longitudinal tie bar to a position wherein the shoulders on the transverse tie member are free from the shoulders on the transversely spaced lugs, and the end portions of the transverse tie member are spaced longitudinally of the frame beyond the upper surface of the lugs so that the transverse tie member may be tilted relative to the frame to permit greater ease of access to the dies while the longitudinal tie bar is in place. 5
2. In a horizontal forging machine having a horizontal frame, one portion thereof being substantially U-shaped in upright cross section, transversely spaced lugs at the free ends of the U-shaped portion respectively and extending upwardly of the frame and terminating longitudinally of the frame short of the ends of the frame, clamping dies relatively movable laterally of the frame within the U-shaped portion and buttressed laterally thereby, a ram and cooperating die relatively movable longitudinally of the frame, whereby said U-shaped portion is stressed during operation and tends to spread transversely of the frame, a longitudinal tie bar reinforcing the frame longitudinally, said longitudinal tie bar being offset laterally of the frame from the work engaging plane of the clamping dies, a transverse tie member having inwardly facing shoulders near the ends thereof, said lugs having outwardly facing shoulders in abutting relation to the inwardly facing shoulders, said longitudinal tie bar having a portion overlying a portion of the transverse tie member, said transverse tie member normally being in a position forwardly of the gripping dies and being movable along the longitudinal tie bar to a position wherein the shoulders on the transverse tie member are free from the shoulders on the transversely spaced lugs and the end portions of the transverse tie member are offset from the upper surfaces of the lugs so that the transverse tie member can be removed from its clamping position relative to the frame to permit greater ease of access to the dies while the longitudinal tie bar remains in place by sliding the transverse tie member along the longitudinal member to a position beyond the lugs and then tilting the transverse member. 10 15 20 25 30 35 40 45 50 55
3. In a horizontal forging machine having a horizontal frame, one portion thereof being substantially U-shaped in upright cross section, transversely spaced lugs at the free ends of the U-shaped portion respectively and extending upwardly of the frame and terminating longitudinally of the frame short of the ends of the frame, clamping dies relatively movable laterally of the frame within the U-shaped portion and buttressed laterally thereby, a ram and cooperating die relatively movable longitudinally of the frame, whereby said U-shaped portion is stressed during operation and tends to spread transversely of the frame, a longitudinal tie bar reinforcing the frame longitudinally, said longitudinal tie bar being offset laterally of the frame from the work engaging plane of the gripping dies, a transverse tie member having inwardly facing shoulders near the ends thereof, said lugs having outwardly facing shoulders in abutting relation to the inwardly facing shoulders, said longitudinal tie bar having a portion overlying a portion of the transverse tie member, said transverse tie member normally being in a position forwardly of the gripping dies and being movable along the longitudinal tie bar to a position wherein the shoulders on the transverse tie member are free from the shoulders on the transversely spaced lugs and the end portions of the transverse tie member are offset from the upper surfaces of the lugs so that the transverse tie member can be removed from its clamping position relative to the frame to permit greater ease of access to the dies while the longitudinal tie bar remains in place by sliding the transverse tie member along the longitudinal member to a position beyond the lugs and then tilting the transverse member. 35 40 45 50 55

WILLIAM W. CRILEY.
